DESCRIPTION

FIG. 1 is an isometric view of a combination leash with stirrup buckle;

FIG. 2 is a front elevation view thereof;

FIG. 3 is rear elevation view thereof;

FIG. 4 is a left elevation view thereof;

FIG. 5 is a right elevation view thereof;

FIG. 6 is a top elevation view thereof; and,

FIG. 7 is a bottom elevation view thereof.

The broken lines shown in the drawings illustrate portions of the combination leash with stirrup buckle that form no part of the claimed design.

The combination leash with stirrup buckle is shown with a symbolic break in its length. The appearance of any portion of the article between the break lines forms no part of the claimed design.
